CLAIM

The ornamental design for a pivoting arm assembly for an electronic display, as shown and described.

DESCRIPTION

FIG. 1 is a front perspective view of a pivoting arm assembly for an electronic display according to the invention;

FIG. 2 is a front elevation view of the pivoting arm assembly for an electronic display depicted in FIG. 1;

FIG. 3 is a rear elevation view of the pivoting arm assembly for an electronic display depicted in FIG. 1;

FIG. 4 is a top plan view of the pivoting arm assembly for an electronic display depicted in FIG. 1;

FIG. 5 is a bottom plan view of the pivoting arm assembly for an electronic display depicted in FIG. 1;

FIG. 6 is a side elevation view of the pivoting arm assembly for an electronic display depicted in FIG. 1; and,

FIG. 7 is an opposing side elevation view of the pivoting arm assembly for an electronic display depicted in FIG. 1.
